7 Claims. (Cl. 235—200)

This invention relates to hydraulic computing devices and particularly to a hydraulic system producing an output signal which is the product of a plurality of variables.

As is generally well-known in the art, multiplication of sensed variables can be effectuated by bleeding hydraulic fluid through suitably disposed restrictions. The variables intended to be measured serve to adjust the area of variable restrictions in order to control the pressure drop across cooperating fixed restrictions for eventually producing hydraulic pressure indicative of the product of the signals sensed. The hydraulic circuitry forming the hydraulic multiplication system generally comprises a network of branch parallelly disposed flow lines wherein each of the branches generally contain a fixed and a variable restriction disposed in series relationship with each other. Successive branch lines are connected intermediate the fixed and variable restrictions and the variable restriction in each of the branch lines are varied as a function of the variable being sensed. Each of the branch lines ultimately communicate with the drain pressure which is held at some constant referenced pressure value. The pressure intermediate the fixed and variable restriction in the last branch is indicative of the pressure being multiplied; hence, its product. This pressure output signal can then be utilized as a control signal.

In the heretofore known hydraulic multiplication systems several problems were attendant which limited their use. One of these problems is that the change of a variable restriction in one of the branches of the computing circuitry disturbs the hydraulic pressure setup by the computing mechanism in the adjacent branches resulting in an error. Another one of these problems is that the Reynolds number effect through the various orifices owing to the changes in area produces another error. Still another problem is that the effective hydraulic multiplication obtainable by one of the variables in each of the branches is limited. This is due to the fact that if a single variable restrictor is utilized to effectuate multiplication through a substantial range, since the area has to vary substantially, errors are noted in the extremity of the range.

It is, therefore, an object of this invention to obviate the problems noted in the immediate above paragraph.

A still further object of this invention is to provide in a hydraulic multiplication system as described, means for switching from one variable to another or the values in between for obtaining the product thereof.

Other features and advantages will be apparent from the specification and claims and from the accompanying drawings which illustrate an embodiment of the invention.

FIG. 1 is a hydraulic multiplication system shown in schematic illustrating this invention.

FIG. 2 is a hydraulic schematic illustrating this invention wherein it is desired to switch between two variables or obtaining the value therebetween.

FIG. 3 is a graphical illustration showing the values of the variables which are selectively multiplied by the scheme shown in FIG. 2.

2

Referring now to FIG. 1 which shows a hydraulic computing system comprising branch 1 and branch 2. Fluid is directed from reservoir 10 through pump 12 to fixed orifice or restriction 14 via line 16. Sensed variable 5 26 varies the area of variable orifice 18 and hence, the flow through line 16 for controlling the pressure drop across fixed restriction 14. Fluid discharging through variable restriction 18 is returned to drain via line 20, drain pressure regulator generally indicated by numeral 22 and line 24. By virtue of the serially connected restrictions and the selection of the area ratio, the pressure intermediate fixed restriction 14 and variable restriction 18 is made proportional to the value of sensed variable 26. Fluid intermediate fixed restriction 14 and variable restriction 18 is directed through line 28 to variable restriction 30 which varies as a function of sensed variable indicated generally by numeral 32. Variable restriction 30 serves to establish the pressure between fixed restriction 34 and itself for establishing desired pressure in one-half of the hydraulic network of branch 2. Fluid discharging from fixed restriction 34 is vented to drain via line 20, drain pressure regulator 22 and line 24. A portion of the fluid is directed to a branch line 36 which also contains fixed restriction 38 and variable restriction 40 20 for establishing the pressure in the other half of branch 2. Variable restriction 40 serves to establish the pressure between fixed restriction 38 and itself.

In accordance with this invention variable restriction 40 and the variable restriction 30 are ganged so that when variable restriction 30 closes, the variable restriction 40 opens a corresponding amount and vice versa. The addition of the second branch in branch 2 serves to effectuate increased multiplication without evidencing additional attendant errors since the impedance of the network is held at a constant value. Since the restriction 30 is upstream of restriction 34 and restriction 40 is downstream of restriction 38, the Reynolds' number effect in the first half of branch 2 compensates the Reynolds' number effect in the second half of branch 2. The arrangement of restrictors minimizes the Reynolds number errors. It will be noted that by the judicious location of valve 30 total flow through both lines 28 and 36 remain constant, providing a constant impedance.

A useful output may be obtained which is indicative of the products of the sensed variables by suitable transducer mechanism indicated by numeral 42. Fluid intermediate fixed restriction 38 and variable restriction 40 is directed to the left-hand end of piston 44 via line 46. The force seen by piston 44 is counteracted by the referenced pressure set up by drain pressure regulator 22 and the force created by spring 43. Hence, the movement of piston 44 is indicative of the product of the variable being sensed.

In order to effectuate multiplication hydraulically it is 55 necessary to provide means for maintaining the pressure upstream of orifice 14 at a constant value. This may be done by utilizing any suitable type of pressure regulator shown in blank by numeral 47 and to regulate the pressure of drain 20 at some constant referenced value. It is preferable to reference the drain pressure to an absolute dataum value. Drain pressure regulator 22 serves this purpose. Pressure regulator 22 comprises bellows 50, pilot valve 52 and suitable flow lines to be described hereinbelow. Fluid discharging from line 20 is admitted in

cavity 54 creating a force externally of bellows 50 opposing the force of spring 56 located internally thereof. A portion of the fluid is admitted into chamber 58 for acting on the upper end of pilot valve 52 so that the combined forces created by the fluid in cavity 58 and the force created by the fluid acting against spring 56 serve to position the pilot valve for metering fluid entering therein through line 69 and line 62 to line 24. Whenever the pressure deviates from the values selected by spring 56, bellows 50, sensing this deviation, positions the pilot valve 52 for holding the pressure in line 20 at the desired constant value.

As disclosed in the above description, the pressure upstream of fixed restriction 14 is held at some constant value. Additional multiplication may be had by varying this pressure in accordance with another sensed variable; as for example, structure shown in my application entitled, "Hydraulic Isochronous Droop Governor," recently filed in the Patent Office and assigned to the same assignee, may serve this purpose and reference is hereby made thereto. This application filed on May 25, 1964 bears Ser. No. 369,849 and now issued as Patent No. 3,279,483. For a theoretical understanding for obtaining multiplication hydraulically, reference is also made to my application Ser. No. 337,904, filed on Jan. 15, 1964, and application Ser. No. 318,671, filed on Oct. 24, 1963, now issued as Patent No. 3,283,499, by F. E. Scheidler, both of which are assigned to the same assignee.

Next referring to FIGS. 2 and 3 which are designed to select one of two variables or the value there-between to be multiplied in the hydraulic computing system. As noted in FIG. 3, it is desired to multiply the value of Z^X (raised to some exponential value). Line 60 represents the situation where X equals an exponential value equal to T and line 62 represents an exponential value where X equals S . Between line 60 and line 62 X will equal some value intermediate the values of S and T .

Now referring back to FIG. 2, all like reference numerals are identical to the structure shown in connection with FIG. 1. For the sake of convenience a detailed description of like parts are omitted to facilitate in the explanation of this invention. As noted above, the pressure in line 16 is held at some constant value. Variable restriction 18 responding to some sensed variable generally indicated by numeral 26 serves to regulate the pressure drop across fixed restriction 14. The fluid is then directed into branch 2 which comprises a pair of parallelly disposed flow lines to be described hereinbelow. Fluid intermediate of fixed restriction 14 and variable restriction 18 is directed to fixed restriction 62 through lines 64 and 66. Variable restriction 68 responding to sensed variable 70 which is equal to Z^T as noted in FIG. 3 serves to regulate the pressure drop across restriction 62. Simultaneously, fluid in line 64 is directed to fixed restriction 72 and then to variable restriction 74. Variable restriction 74 responds to sensed variable 76 which is equal to Z^S as indicated in FIG. 3. Both variable restrictions 68 and 74 may be contoured to define the function $Z^T + Z^S$. In that case, both restrictions will move as a function of variable Z^X . As noted from the drawing of FIG. 2 the fluid discharging from variable restrictions 18, 68 and 74 discharge into drain line 20 which is held constant to some absolute value in the same manner as was described in connection with FIG. 1.

In accordance with this invention a pair of variable restrictions 78 and 80 are disposed in passage 82 which interconnects line 66 and line 64 downstream of both restrictions 62 and 72. The output signal which is a product of the variables being sensed may be selectively made by opening 78 and closing 80 or vice versa which is done manually by lever 83. Obviously, it is desirable to gang these two restrictions so that when one opens the other closes and vice versa. The useful output signal is then directed through line 84 to some suitable transducer mechanism as for example the mechanism indicated by numeral 42 shown in FIG. 1. As was indicated above in

connection with the description of FIG. 3 the variable Z^X may be selected at some value intermediate the values of the exponential S and T . This is accomplished by selecting the position of variable restrictors 78 and 80 at some point intermediate their full open and full closed positions.

It is to be understood that the invention is not limited to the specific embodiment herein illustrated and described but may be used in other ways without departure from its spirit as defined by the following claims.

I claim:

- Means for hydraulically computing the products of sensed variables comprising a pair of parallelly disposed fluid branches, one of said branches having a first flow line and a pair of serially disposed restrictions, means for varying the area of one of said restrictions as a function of a sensed variable, the other branch having second and third parallelly disposed fluid flow lines each of which contain a pair of restrictions, a drain, said second fluid flow line interconnecting said first fluid flow line at a point intermediate the two restrictions in the first branch and drain, means for varying the area of the upstream restriction in said second fluid flow line as a function of a sensed variable, said third fluid flow line interconnecting said drain and said second fluid flow line at a point just downstream of the variable restriction and upstream of the other restriction disposed in said second flow line, means for varying the area of the downstream restriction in said third flow line as a function of the movement of said variable restriction in said second flow line and means for regulating the pressure in said drain.
- In means as defined in claim 1 wherein said regulating means maintains the pressure in said drain at a constant value.
- In means as defined in claim 1 including a pressure transducer means and a conduit interconnecting said pressure transducer means and said third flow line at a point intermediate the restrictions disposed therein.
- In a hydraulic computing system for producing a signal commensurate with the product of a plurality of sensed variables, a source of fluid under pressure, a regulated pressurized drain, a first fixed and a first variable restriction in series relation therewith, first passage means leading fluid from said source through said first fixed restriction, said first variable restriction to said drain, a second fixed restriction, a second variable restriction connected in series with and located upstream with respect to said second fixed restriction, second passage means leading fluid from a point intermediate said first fixed restriction and said first variable restriction through said second variable restriction, said second fixed restriction to drain, a third fixed restriction, a third variable restriction in series relation with and located downstream with respect to said third fixed restriction, said third variable restriction movable as a function of the movement of the second variable restriction and third passage means leading fluid from a point intermediate said second fixed restriction, said second variable restriction to drain.
- In a hydraulic computing system having a source of pressure and a drain, means for regulating the pressure of said source and of said drain, a first passage interconnecting said source and drain, a first fixed and a first variable restriction serially disposed in said passage, a second passage interconnecting said drain and said first passage at a point intermediate said first fixed restriction and said first variable restriction, a second fixed restriction and a second variable restriction serially disposed in said second passage, a third passage interconnecting said drain and said first passage at a point intermediate said first fixed restriction and said first variable restriction, a third fixed restriction and a third variable restriction serially disposed in said third passage, a fourth passage interconnecting said second passage at a point intermediate said second fixed restriction and second variable restriction and said third passage at a point intermediate

said third fixed restriction and third variable restriction, a pair of ganged variable restrictions disposed in said fourth passage, and means for selectively positioning said pair of variables such that when one opens the other closes and vice versa.

6. In a hydraulic computing system as claimed in claim 5 including means responsive to sensed variables for varying the area of said second variable restriction and said third variable restriction.

7. In a hydraulic computing system as claimed in claim 5 including an output receiving device and a fifth passage interconnecting said device and said fourth pas-

sage at a point intermediate the pair of ganged variable restrictions.
